UNITED STATES PATENT OFFICE.

JOSEPH S. FAUTH, OF BLOOMFIELD, NEW JERSEY.

SPARK-PLUG.

1,309,192.

Specification of Letters Patent.

Patented July 8, 1919.

Application filed January 26, 1918. Serial No. 213,956.

To all whom it may concern:

Be it known that I, JOSEPH S. FAUTH, a citizen of the United States, residing at Bloomfield, in the county of Essex and State 5 of New Jersey, have invented new and useful Improvements in Spark-Plugs, of which the following is a specification.

This invention relates to improvements in spark plugs adapted for use in igniting the 10 gas in internal combustion engines.

One object of the invention is to provide an improved form of spark plug which embodies a movable electrode which is actuated by the vibratory action of the engine and 15 also by the inrush and explosion of the charge, and which prevents the deposition of carbon at the sparking point and thereby readily increases the efficiency of the spark plug and of the engine in which the spark 20 plug is used.

Another object of the invention is to provide an improved spark plug which embodies a core or insulating sleeve which comprises an inner section of mica and an outer 25 section or member of fiber, detachably connected to the mica section by the conducting rod which forms the inner electrode.

With the above and other objects in view the invention consists in the construction, 30 combination and arrangement of devices hereinafter described and claimed.

In the accompanying drawings:—

Figure 1 is a vertical central sectional view of a spark plug constructed and arranged in accordance with my invention. 35

Fig. 2 is a bottom plan of the same.

Fig. 3 is a detailed sectional view of the same on a larger scale.

The base 1 of the spark plug is here shown 40 as provided with the usual screw plug 2 and with the usual polygonal head 3 which may be engaged and turned by a wrench. At the inner end of the screw plug 2 is a cross bar 4 which extends centrally thereacross, the said cross bar being provided with a 45 central circular opening 5 the wall of which is chamfered on opposite side to form an annular substantially knife like edge 6.

A movable electrode nut is provided which 50 is in the shape of a dumb-bell comprising a

shank 8 and enlarged heads or ends 9 which are substantially spherical in form. The shanks or narrowed central portions of the movable electrodes extend through the opening 5 so that the said movable electrode is 55 loosely mounted in said opening and is adapted to describe oscillating motions.

The core of the spark plug comprises an inner member 10 which is made of mica and an outer member 11 which is made of fiber. 60 The inner member is fitted in the base and is formed with an enlarged annular shoulder 12 which is engaged and held and firmly clamped in place in the base by means of the usual sleeve nut 13. A conductor rod 14 extends centrally through the members 10 and 11 of the core and is provided at the inner 65 ends with an enlarged semi-spherical head 15 which forms an electrode which is opposed to a movable electrode 8. A jam nut 16, which is preferably made of brass is screwed to the outer end of the conductor rod and bears on the outer end of the fiber member 11 of the core, said jam nut co-acting with the conductor rod and with the 70 head or electrode 15 of the conductor rod to firmly and yet detachably secure the members 10 and 11 of the core together.

Owing to the construction of the movable electrode with the oppositely arranged head 80 9, and the provision of the oppositely beveled side of the wall of the opening 5 in which the stem or shank of the said electrode is mounted, the said electrode is balanced and is caused to move and swing 85 from side to side when the engine is in operation and to continually strike the electrode 15 and thereby prevent the deposition of carbon thereon.

Having thus described my invention I 90 claim:—

1. A spark plug having a fixed electrode and also having a bar spaced from said fixed electrode and provided with an opening, and a movable electrode comprising a 95 shank and enlarged heads at the opposite ends of the shank, said shank extending through and being loosely mounted in said opening for oscillation and the heads being on opposite sides of said bar. 100

2. A spark plug having a fixed electrode and also having a bar spaced from said fixed electrode and provided with a circular opening opposite said fixed electrode, the wall of said opening being beveled on opposite sides, and a movable electrode loosely mounted for oscillatory movement in said opening, said

movable electrode comprising a shank extending through said opening and loose therein and enlarged heads at the ends of said shank.

In testimony whereof I affix my signature.

JOSEPH S. FAUTH.
